UNITED STATES PATENT OFFICE.

CLYDE G. LONGNECKER, OF CHICAGO, ILLINOIS.

DESIGN FOR AN AUTOMOBILE BUMPER OR SIMILAR ARTICLE.

Application filed November 20, 1922. Serial No. 4,336. Term of patent 14 years.

To all whom it may concern:

Be it known that I, CLYDE G. LONGNECKER, a citizen of the United States, residing at Chicago, in the county of Cook and State of Illinois, have invented a new, original, and ornamental Design for an Automobile Bumper or Similar Article, of which the following is a specification, reference being had to the accompanying drawing, forming a part thereof.

Figure 1 is a front elevation of my ornamental design of bumper;

Figure 2 is a top elevation of the same, and

Figure 3 is a side elevation of the same.

I claim:

The ornamental design for an automobile bumper or similar article, as shown.

CLYDE G. LONGNECKER.
